UNITED STATES PATENT OFFICE

LETH JENSEN, OF PARIS, FRANCE

CARBURETOR FOR INTERNAL-COMBUSTION ENGINES

Application filed May 13, 1926, Serial No. 108,896, and in France May 22, 1925.

The present invention has for its object a carburetor for internal combustion engines.

This carburetor, which can be readily mounted on various engines, ensures the formation of a mixture of good proportions of air and petrol at all speeds of the engine and permits adjustment at certain periods so as to permit of the adaptation of the carburetor to very different conditions, such as 10 operation in cold weather or in hot weather.

In connection with carburetors for internal combustion engines suggestions have been made previously to provide between the float chamber and the induction pipe of the engine 15 a rotatable plug serving to control the passage of the mixture of air and petrol to the engine.

According to the present invention an open ended tube provided with a calibrated hole 20 adjacent each end thereof is removably fitted into a central passage in a jet carrier, the holes adjacent the opposite ends of the tube being of different size, while the tube is reversible so that one or other of said holes may be 25 brought into the operative position for controlling the passage of petrol, one of said holes for example being adapted for use in cold weather while the other is adapted for use in hot weather.

30 The invention will now be described with reference to the accompanying drawings, wherein

Figure 1 illustrates a vertical section of the carburetor.

35 Figures 2 and 3 are horizontal sections on the line A—B of Figure 1, Figure 2 showing the parts in position for normal running and Figure 3 showing the parts in position for slow running.

40 Figure 4 is a side elevation of the nozzle holder.

Figure 5 is a longitudinal section of the same.

Figure 6 is a plan view of the same.

45 Figure 7 is a side elevation of the admission plug and

Figures 8 and 9 are respectively a plan view and a vertical section of said plug.

50 Figure 10 is a side elevation of the nozzle tube.

Figures 11 and 12 are respectively side elevation and plan views of the lid.

Figure 13 is a side elevation of the regulating float.

Figure 14 is an elevation view of a modified 55 form of carburetor.

Figure 15 is a longitudinal section of the same carburetor taken along the line II—II in Figure 14.

Figure 16 represents a diametrical section 60 of a valve or plug forming a detail modification shown in Figs. 14 and 15 in which is a vent for admission at low speeds.

Figure 17 is a transverse section of the carburetor taken along the line XVII—XVII of 65 Figure 15.

The carburetor shown in Figures 1 to 13 inclusive, is provided with a body 1 with a flange 2 for securing it to the engine. This body 1 has a main air intake pipe 3 and an outlet pipe 4 for supplying the mixture to the engine.

Between the two pipes 3 and 4 there is arranged a member 5 which will be referred to as the nozzle carrier and which is surrounded by a controlling plug 6 (illustrated separately 70 in Figures 7, 8 and 9). This plug 6 is fitted on the nozzle carrier by which it is guided and it can turn without friction in a circular recess formed in the body 1 between the pipes 3 and 4. It is of general cylindrical shape, 75 hollow and provided with two main orifices 6', 6' which are adapted, according to the angle of rotation, to coincide partially or completely with the sections of the pipes 3 and 4. The plug 6 is also provided with a small lateral orifice 6'' for slow running, and in its lower face with a groove 6A which forms communication between the two main orifices 6'.

The portion of the nozzle carrier 5 between 80 the pipes 3 and 4 is of elongated section as shown in Figures 2 and 3 or it may be circular, with its central portion of reduced diameter, as shown in Figures 4 to 6, so as to divide the main stream of air entering through the pipe 3 into two streams which re-join beyond the nozzle carrier.

85 An auxiliary air inlet 7 is formed by a lateral passage provided in the body 1 and which may be partly or completely uncovered by 90

100

means of a slider 8 adjusted and suitably guided on the outer cylindrical surface of the body 1.

The nozzle carrier 5 is secured to the body 1 by means of a nut 9, and is extended upwardly by a cylindrical portion 5' and downwardly by a cylindrical portion 5''.

Along its whole length it is provided with a central passage 10 which terminates at the bottom of the part 5'' in an orifice 10' provided for the passage for fuel and for a rod 26, connected to a float 24. Small lateral orifices 11 are also provided in the lower end of the part 5'' and communicate with the orifice 10'.

At a certain point of the length of this central recess 10 there opens a small inclined passage 12 which terminates on the lateral surface of the part 5 at the side of the pipe 4.

20 Into the central passage 10 is placed a tube 13 which rests on the bottom of the passage, extends along the whole length thereof and passes beyond its upper end. This tube 13 is of smaller diameter than the recess 10 in such a manner as to divide the passage into a central space and an annular space 14. The lower end of the inclined passage 12 leads from this annular space 14, the opening thereof being at about the level of fuel in the float 30 chamber 20.

The tube 13 (Figure 10) is provided adjacent its ends with two small holes 13' and 13'' the lowermost hole serving for the passage of fuel from the central space to the annular 35 space 14.

These two holes are of different diameter and calibrated in such a manner as to serve one as the nozzle during summer time and the other as the nozzle for winter time.

40 As the tube 13 is simply resting in the cylindrical recess 10 it thus suffices, according to the surrounding temperature, to place the tube in the recess in such a manner as to place in the bottom of the latter the hole 13' or 13'' 45 which is to serve as a nozzle, the hole at the top being inoperative as a nozzle and serving solely for a small initial admission of air as hereinafter described. The facility of removing and replacing this tube for the initial 50 adjustment of the carburetor will be readily seen. By the use of two or three tubes with different size holes it will be seen that the carburetor can be adjusted to suit the prevailing atmospheric conditions. It may be 55 mentioned that the nozzle tube 13 may be removed by hand and without the necessity of closing the supply of fuel.

The lower end of the tube 13 bears on the truncated bottom of the cylindrical recess 10 60 and its upper end bears against a cap 15 which is screwed on the screw-threaded end on the part 5' of the nozzle carrier 5.

This cap 15 is provided with a hole at the center through which passes the rod 26 of 65 the float 24, and for the admission of air.

The plug 6 is provided with a portion forming a flange 6''' to which is secured a stud 16, connected to rod mechanism or operated in any suitable manner, by means of which the driver can turn the plug 6 into the required angle for controlling the admission of air.

The upper part 6''' of the plug is covered by a cover 17 of which the periphery 17' engages with a circular recess in the body 1. The cover 17 is secured in position by a nut 18 screwed on the screw thread of the portion 5' of the nozzle carrier. This cover is provided with a groove through which passes the stud 16 and which limits the movements of the latter and thus of the plug 6. This construction permits the operating mechanism to be disposed in such a manner that this may be actuated either by pulling or pushing according to the case of application.

This cover 17, of dome shape, (Figures 11 and 12) is slightly flexible in such a manner that when tightening the nut 18 it tends to slightly flatten and thus tightens its periphery 17' in the circular recess of the body 1.

In the body 1 there is provided a passage 19 adapted to form communication between the outer atmosphere and the interior of the float chamber 20.

The float chamber 20 is secured to the underside of the body 1 by screw threading at 20' or by another method of securing.

The fuel enters the bottom of the chamber 20 through a vertical passage 21 from a filter 22 of any suitable construction, which receives the fuel from a tank by the pipe 23.

The float 24 is provided at its lower end with a valve member 25 which seats in the opening of the inlet passage 21 for the fuel. To the bottom of the float 24 there is secured the vertical rod 26 which passes through the orifice 10' at the bottom of the recess 10 of the nozzle carrier, extends along the whole length of the tube 13 and beyond the cap 15.

The operation of the carburetor is as follows:—

For starting, the chamber 20 is flooded by raising the float 24 by means of the rod 26 which projects beyond the cap 15.

The liquid then enters the chamber 20 driving out the air which escapes through the passage 19.

When the level of fuel in the chamber 20 is sufficient to enable the float 24 to float the rod 26 is released and the liquid continues to enter the chamber 20, through the passage 21, and subsequently flow over the edge 24' of the float 24 into the interior of the latter thus filling this.

When the float is filled it descends and the valve 25 closes the inlet passage 21 for the fuel.

The lower portion of the nozzle carrier 5 is thus immersed in the fuel, contained in the float 24 which passes into the nozzle carrier through the orifices 10' and 11 to the

same level as in the float 24, and by passing through the hole in the lower end of the tube 13 passes to the same level in the annular space 14 around the tube 13.

5 From the annular space 14 the fuel, mixed with a small quantity of air entering the upper part of the annular space 14 is drawn through the inclined passage 12.

10 The admission plug 6, which is actuated by the stud 16, is set for starting in the position just beyond that shown in Figure 3 so as to cover the inclined passage 12.

15 In this position air from the pipe 3 and fuel from the passage 12 is drawn through the small hole 6" provided in the plug 6 on the side of the engine and situated at the level of the inclined passage 12.

20 At slow speed the admission of air is effected through the lateral orifice 7 of which the area of opening is adjusted by the slider 8. This slider may be actuated at will from the driver's seat or may be fixed in the position giving the best result.

25 When accelerating the plug 6 is gradually moved to the position shown in Figure 2 so that during this movement the wall of the plug gradually closes the orifice 7 for additional air (Figure 2) and thus all the air drawn in can only enter through the pipe 3 and must pass on each side of the body of the nozzle carrier 5 and is mixed intimately with the rich mixture arriving through the passage 12. The complete mixing and homogeneity of the mixture are ensured by reason of the fact that the passage 12 for the rich mixture being inclined, the mixture which it supplies is projected upwardly into the inlet pipe 4 for the mixture. It will be understood that any vacuum which may be 40 produced at high speeds in the pipe 4 is destroyed by the air which passes from one orifice 6' of the plug to the other orifice 6" by the auxiliary passage formed between these two orifices by the groove 6A.

45 These different peculiarities of construction enable a carburetor to be produced of simple construction and of little expense, and of small size which can be easily applied to engines of different types.

50 In the modification shown in Figures 14 to 17 inclusive the jet holder 5 can be constructed to operate as principal diffuser in case the carburetor is fitted to certain types of engines.

55 To this end, the central portion of the nozzle-holder has a concave circular surface on the outside and this surface is pierced with several rows of emulsion holes 27-27' communicating, at the centre of the part, with the hollow space 10.

A circular groove 28, arranged at the bottom of the central portion of the nozzle-holder, causes the holes 27' to communicate with one another, these holes being arranged according to the lowest row.

As will be observed from Figure 16, vents 29 of suitable number and shape, are arranged through the side of the circular base of the plug 6. The function of these vents is to establish communication between the nozzle 13 and the passages 3 and 4 according to the path formed by the holes 27' and the groove 28.

70 The vents 29 are arranged in such a way that they come progressively in front of the openings 3 and 4 according as the plug 6 is turned in the direction of the closing of the principal intakes.

75 When running at a slow speed, or when starting up the engine to which the carburetor is added since direct communication of the openings 3 and 4 is prevented by the sides of the plug, feeding is carried out exclusively by the vent or vents 29, directed towards the tubing 4, section of the orifices 80 of these vents being able to be adjusted on occluding more or less, those orifices with the edge of the tubing 4.

85 In this way, the device enables exact mixture proportions, to be obtained, according to needs.

90 With respect to the circular plug openings, the position of the vents 29 in the circumference of the plug 6 is such that when accelerating, that is to say at the moment those 95 openings are uncovered on one of the sides of the interior orifices of the tubings, the principal admission of gases begins before the orifices of the vents 29 are completely hidden behind the side opposite the tubings. 100

Under these conditions, it will be understood that a passage from slow to higher engine speeds takes place progressively, the sections of the intake orifices of the tubing 4 constantly increasing during acceleration. 105

On the other hand, admission of the rich mixture which, during slow running, only took place through the vents 29, is now operated according as the plug 6 rotates, through an increasing number of openings of the 110 emulsion holes 27-27', as fast as they are uncovered and subjected to the engine's suction.

As can be seen from Figures 14 and 17, this form of carburetor is supplied with a 115 hot-air intake tubing 31 that can be brought into connection with the secondary air intake 7. The aim of this hot-air intake is to facilitate starting of the engine when cold, and to supply hot air at all intermediary engine speeds. When starting up, control of the hot air intake is ensured by means of a diaphragm or axis shutter 32 the position of which can be regulated by the driver. Apart from starting up, the diaphragm remains 120 open and the hot-air intake is adjusted automatically according to the position of the plug 6 in relation to the tubing conveying hot air. 125

130 These different particularities and these

different methods of construction and grouping of means permit establishment, in all cases, of a carburetor that is simple and not very costly to manufacture, not very bulky and capable of being adapted easily to different types of engines.

It is to be understood that this carburetor just described, as well as the special shapes and arrangements mentioned for the different organs and as are shown in the attached drawings, only constitute examples of application of the invention to which all modifications can be added with regard to the shape, arrangement and even the number of parts and elements constituting the carburetor, without departing from the scope of the invention by so doing.

What I claim is:

A carburetor comprising a body having a float chamber, cup-shaped submersible float in said float chamber, liquid fuel eduction means extending to a point adjacent the bottom of said float, the latter being provided with a stem extending through said liquid fuel eduction means to the exterior of the carburetor.

In testimony whereof I have signed my name to this specification.

LETH JENSEN.
